Church, Va.

Application September 20, 1940, Serial No. 357,633

31 Claims. (Cl. 120—32)

The present invention relates in general to tabulating machines and in particular to a tabulating machine for bringing similar portions of each of a plurality of data sheets simultaneously into position for tabulation of data therefrom. Such sheets may be any record sheets of substantially identical form bearing on corresponding portions entries of like classification to be tabulated.

For a general discussion of the accounting problems to which this device offers a solution, reference may be had to Patent No. 2,041,256, issued May 19, 1936 to R. D. McCormack, in which the matter is examined fully from the accountant's point of view. The present invention is an improvement in the art as represented by the disclosure of the above prior patent.

The main object of the present invention is the provision of a machine capable of manipulating a multiplicity of sheets, for example, a half-month's daily sales summaries with a minimum amount of friction and minimum power requirement for its operation, and capable of handling sets of sheets differing widely in size and form and of various grades of paper, even very flimsy paper and paper which has been folded in the mails without danger of tearing or fouling.

An ancillary object is the provision of a feed roll unit around and over which a data sheet may be fed in a loop in smooth, firm direct contact with the roll without exertion of tension or other strains on the sheet or added friction in the moving parts or on the surface of the sheets.

Another object is to improve the strength, sturdiness and wearing qualities of machines of the present type by the elimination of carrier webs or belts and with resultant accuracy of control and elimination of lost motion.

A further object is to improve the compactness of the device and the arrangement of the sheet holding units whereby a device of relatively large capacity may be conveniently used on an ordinary desk.

A further object is to provide an arrangement whereby the data sheets are discharged in a stack in the order in which they were loaded into the machine.

Various other objects and advantages of the invention will be apparent from a perusal of the following specification and the drawings accompanying the same.

In the drawings:

Figure 1 is a perspective view of the assembled device;

Figure 2 is a front elevation with the front portion of the casing removed;

Figure 3 is a section on the line 3—3 of Figure 2;

Figure 4 is a section on the line 4—4 of Figure 2;

Figure 5 is a side elevation of the device looking from the right in Figure 1, showing part of the seal plate removed and some of the individual cut-off valves removed and some in section;

Figure 6 is an enlarged fragmentary detail view of a portion of Figure 3 showing the position of the feed rolls and guide members in the operating position;

Figure 7 is a view similar to Figure 6, but with the parts in the loading position;

Figure 8 is a section on the line 8—8 of Figure 6;

Figure 9 is a section on the line 9—9 of Figure 4;

Figure 10 is a fragmentary view of part of Figure 4 with the distributing valve removed to show the parts in the manifolds;

Figure 11 is a fragmentary detail view similar to Figure 10 with the distributing valve partly in section and in one of its full connecting positions;

Figure 12 is a view similar to Figure 11 but showing the distributing valve in intermediate position;

Figure 13 is a fragmentary sectional view on the line 13—13 of Figure 4, on a slightly larger scale;

Figure 14 is a section on line 14—14 of Figure 13;

Figure 15 is a section on the line 15—15 of Figure 8 showing the shaft stop pin connection;

Figure 16 is a detail, perspective view of a feed roll showing the arrangement of the suction slots for holding the work;

Figure 17 is a similar view of the guide member showing the suction slots therein forming a retaining work holder;

Figure 18 is a fragmentary detail view showing the jointed end of the guide member disassembled;

Figure 19 is a fragmentary perspective view of the rear or discharge end of the device; and

Figure 20 is a fragmentary perspective view of the inside of the front cover showing the inwardly curved flanges.

Referring to the drawings and first to Figures 1 and 3, the device comprises in general a housing or casing consisting of a continuous metallic sheet

element 21 forming the front, top and back portions, right and left hand end plates 22 and 23 forming the sides, and a base portion 24. The casing is provided in its slanting front portion 5 with a series of horizontally elongated window openings 134 arranged one above the other, behind which are situated a series of feed rolls 25 for feeding a series of data sheets 59 (Figure 7) to bring similar portions of the different sheets 10 simultaneously into view, each through its respective window opening, or data indicating means, for tabulation of data from such data sheets. Below the series of individual window openings 134, is a master window opening 131 through which projects the upper surface of what 15 may be termed a master feed roll 105 operated in synchronism with the individual feed rolls 25 for feeding portions of a master sheet or key sheet into the window opening. The master feed roll 105 is larger than the individual feed rolls, in the present embodiment, substantially twice as large, to afford a more nearly flat platen surface to permit entries to be made upon a sheet carried thereon, for example, a listing of 20 the accumulated totals of the respective items 25 simultaneously presented on form sheets fed by the individual feed rolls 25.

The feed rolls 25 are of hollow cylindrical form, each provided at one end with a hollow concentric journal shaft 60 (Figure 8), and at the other end 30 with a solid concentric journal shaft 141, journaled in end plates 22 and 23, respectively; and upon its cylindrical surface with two or more longitudinal suction slots 62 (Figures 7, 8 and 16) which are cut through to the hollow central space 35 in the roll. The hollow in the feed roll connects with that of the hollow journal shaft so that the whole provides a continuous air-tight passage. The purpose of this is that a form-sheet 59 (Figure 6) when laid over these suction slots may be 40 secured to the feed roll by atmospheric pressure when a vacuum is applied to the hollow journal shaft. To insure a substantially vacuum tight seal between the suction slots and the form sheet, suction slot seals 64 are provided. These 45 are preferably of rubber or similar yielding material molded or otherwise secured to the inner walls of the suction slots near the mating, surface edge of the suction slots but slightly recessed within the feed roll. It will clarify an understanding of their construction as well as their 50 purpose to say that they constitute a cushion lining so positioned within the suction slots that they may be contacted by the form sheet when, and only when, the paper bulged slightly into the 55 slots due to the application of a vacuum. The purposes of these seals are two fold: first, to afford a surface of highly frictional character; second, to provide a yielding seal to complete the air tight retention of hard, form sheets having 60 a rough or rippled surface.

The suction slots with their seals thus form a releasable work-holder carried by the feed roll whereby the work is held on the roll without a rubbing contact between work and holder and 65 without the exertion of lateral pressure on the journal shafts which would result in increased friction.

With each feed roll is associated a movable guide member 26 having a concave cylindrical 70 guide surface portion substantially complementary to the surface of the feed roll for holding or guiding a work sheet into contact with or close proximity to the feed roll. The guide member 75 is of hollow construction mounted on a pair of journal shafts 61 and 75, (Figure 8) one jour-

naled in the side plate 22 and the other in a bearing socket 77 secured to the side plate 23. The purpose of this mounting of the guide member is to permit oscillation thereof toward and away from the feed roll to enable the guide member to be yieldably held against the feed roll and to facilitate loading of the machine in a manner to be later described. It is important that the mating surfaces of the feed rolls and guide members be maintained in close contact along their 10 entire length. From a practical standpoint this would be difficult to arrange if both members were provided with rigid journal shafts, as a small error in alignment might cause heavy contact at one end and little or none at the other. Avoidance of this difficulty has been obtained by providing between each guide member 26 and its journal shaft 75 a floating coupling (Figure 18) comprising an off-set coupling arm 72 fixed to the inner end of the shaft 75 and provided with 20 a pivot 74 pivotally engaging the adjoining end of the guide member through a recess or socket 76 in the guide member at a point radially offset from the axis of the journal shafts 61 and 75 and in a substantially median position with reference 25 to the lateral extent of the concave mating surface of the guide member 26. This relation will be made clear with the statement that the positioning of the recess with respect to the mating surface is for the purpose of applying the 30 contacting effort of the driving shaft 75 and offset arm 72 through the pin and socket equally to all portions of the arc of the concave mating surface of member 26. Thus, alignment of the mating surface is established by contact of the surfaces themselves; any small mechanical error affecting the parallel relationship of a feed roll 35 to its related guide member 26 will be dissipated in the form of a slight displacement of the otherwise coincident axes of journal shaft 75 and its guide member. Similarly the guide member 106 is provided at its left hand end with a floating coupling, not shown, but which it is to be understood is similar in all respects to that 40 shown in Figure 18 and which like those of the other guide members is journaled in a bearing socket 114 (Figure 2) secured to the side plate 23. 45

The concave cylindrical surface portion of each guide member is provided with two or more longitudinal suction slots 63 with suction slot seals 65 (Figures 7 and 17), similar to those of the feed roll, extending through to the interior of the guide member which connects with the hollow journal shaft 61 to provide a continuous air-tight 50 passage in a manner similar to that of the feed roll. Thusly arranged, the suction slots 63 form a retaining work-holder for holding a work sheet in fixed relation to the guide member to retain it stationary relative to the frame of the machine and unaffected by rotation of the feed roll. 55

Under the conditions noted above it will be apparent that if a vacuum be applied through the hollow journal shaft of the feed roll 25 to the suction slot therein, the form-sheet will be held fixed to the feed roll and will move with it 60 when the latter is rotated or oscillated. Similarly if the vacuum be removed from the feed roll suction slots and applied to the suction slots in the guide member 26, the form-sheet will be secured to the guide member and thus retained 65 against movement by the feed roll and held stationary with respect to the frame of the machine. Thus, by repeated oscillation of the feed roll 25, first in a clockwise direction, as viewed from Figure 6, from the position shown in Figure 6 to 70 75

that shown in Figure 7, and then in a counter-clockwise direction back to the position of Figure 6, maintaining a vacuum in the suction slots of only the feed roll during the clockwise movements and in the suction slots of only the guide member in the counter-clockwise movements, the form-sheet 59 (Figure 6) will be fed around the feed roll step-by-step.

For a similar purpose, the master feed roll 105 is provided with suction slots 138 for holding a work sheet in fixed relation to the roll, and a guide member 106 having a concave cylindrical guide surface portion complementary to the surface of the feed roll and urged against the latter by a light spring 116, the guide member 106 having a suction slot 139 in its concave surface portion for retaining a work sheet stationary relative to the machine. Vacuum is supplied to these suction slots through connection with their respective hollow journal shafts 110—113 as indicated in dotted lines in Figure 3. To facilitate the placement of a work sheet on the feed roll 105 the guide member 106 is provided with a lifting ledge 115 (Figures 2 and 3).

For properly supporting and guiding the form sheets 59 in their passage to and away from the feed rolls and effecting the discharge of a series, stacked in the same order as that in which they were loaded into the machine, individual, stationary, sheet supports 120 to 126 (Figure 3) are provided, one below each feed roll. These are in the form of sheet metal vanes or partitions sloping downwardly from below their respective associated feed rolls toward the rear of the machine and toward the rear discharge opening 132, and extending transversely of the machine between vertical end partitions 127 and 128 (Figure 2), to which they may be secured in any known or other suitable manner not shown. Only the bottom and the lower edge of the lowermost support 126 shows in Figure 2, as the front edges of the supports are obscured by the guide members 26 and their lower edges obscured each by the support next below. From Figure 3 it will be seen that the supports 120 to 126 together with the top guiding vane 119 form between them a series of open-ended passageways with their forward open ends terminating substantially in a common plane at the front of the machine, and that near the front open end of each of such passage-ways thus formed is situated one of the feed rolls 25. The top guiding vane 119 by its downwardly curved rear edge directs the top form sheet (and thus the others) away from the back portion of the casing 21. The lowermost support 126 is extended to the rear opening of the machine to form a chute for conveying all the form sheets once they leave their individual guide supports; and the incline of all the supports is such that the form sheets will descend by gravity once they are released from the suction slots of their respective feed rolls. An opening 133 in the rear edge of the lowermost support 126 facilitates removal of the collected sheets.

Similarly, the master feed roll 105 is provided with a pair of discharge vanes 129 and 130 forming a passageway for directing a form sheet from the feed roll 105 through the discharge opening 131 (Figures 1 and 3) at the front of the machine, after the form sheet has been guided to the feed roll over the lower front portion of the casing 21.

Simultaneous operation of all the feed rolls is effected by the operating lever 34 (Figures 1 and

5) which projects through the front of the machine, below and to the right of the series of window openings, within convenient reach of the operator, and is pivoted inside the casing at 33 (Figure 4) upon a member 28 which latter has 5 limited movement of slight extent. The lever 34 is biased in the uppermost position as shown in solid lines in Figure 4 under tension of a retractile spring 39 of sufficient strength to return the lever to the uppermost position after release 10 by an operator from a lower position, for example that shown in dot-and-dash lines.

In the downward movement of the outer end of the operating lever 34 by force applied to the outer end, the lever first pivots about the pivot 15 screw 35 to move the link 28 upwardly through the full extent of its limited motion, for a purpose and in a manner to be later described, and then about the pivot 33 to move the link 36 downwardly, which movement of the operating lever 20 about pivot 35 is limited by a retaining strap 69. Motion is imparted from the link 36 through a pivot screw 37 to a lever arm 80 fixed to the hollow journal shaft 60 of the uppermost feed roll to oscillate said shaft and roller in a counter-clockwise direction as viewed in Figure 4, and a clockwise direction as viewed in Figure 6. From this shaft 60, the motion is further transmitted through a lever arm 99 (Figure 6) fixed to the shaft 60, and through a pivot screw 103 to a 30 synchronizing gang-link member 102 from which motion is transmitted through a plurality of individual lever arms 38, pivoted at one end to the gang-link and at the other end fixed each to one of the journal shafts 60 of the feed rolls 25 as 35 shown in Figure 3. For synchronizing movement of the master feed roll 105 (Figure 3) with the individual feed rolls 25, motion is transmitted from the lever arm 99 to the master feed roll through a link member 101 pivoted at its upper 40 end by a pivot screw 100 to the lever arm 99 at a point intermediate the ends of the lever arm and pivoted at its lower end by a pivot screw 108 to a lever arm 107 fixed to the hollow journal shaft 110 of the master feed roll. By making the pivotal connection 101 to a midpoint on the driving lever arm 99 at a radius substantially half that of the lever arm 107, the angular movement of the master feed roll is reduced to substantially one half that of the series of individual feed rolls, 50 so that notwithstanding the larger diameter of the master feed roll, about twice that of the individual rolls, its peripheral movement is substantially the same, with the result that the advancement of a sheet fed by the master roller 55 will be substantially equal to those of the sheets fed by the individual rolls.

For geometrical reasons there is, of course, an incipient error in too rigid adherence to the ratio 60 just stated, due to the fact that, while the chord of the arc described by pivotal screw 100 is equal to the chord of the arc described by the pivotal screw 108, the included angle of the latter will be somewhat less than one-half of the former 65 so that with a strict adherence to the ratios above mentioned the master roll would lag somewhat behind the individual rolls. It is, therefore, preferable to suitably proportion the ratio of the diameter of the master roll to the radius 70 of its portion of the lever arm 99, to reduce such error to a negligible minimum.

It might also be mentioned at this point that in the present embodiment the awkward operating angles which the various connecting links 75

may sometimes make with the levers to which they are respectively connected have been largely eliminated by making the links as long as the general design of the device will permit, thus reducing the necessary angular displacement of the links themselves. Thus, for example, the drive from the main operating lever 34 has been applied through a long link to the uppermost feed roll 25 since it is the one farthest away. Similarly, the drive for the master feed roll has been taken from the shaft of the same uppermost feed roll since this offers the greatest possible length of connecting link.

From the foregoing it will be seen that repeated operation of the lever 34 will result in repeated, simultaneous oscillation of all the feed rolls through substantially the same peripheral extent. Thus, the work sheets may be fed forward step-by-step around the feed rolls by suitable alternation of the application of a vacuum to the suction slots 62 forming the feeding work-holders carried by the feed rolls 25, and the suction slots 63 forming the retaining work-holder situated in the guide members 26, in synchronism with the forward and backward oscillations of the feed rolls. This causes the work sheets to be held only by the rolls in a forward oscillation, clockwise as viewed in Figure 6, and to be held only by the suction holders in the guide members during a backward oscillation, counterclockwise as viewed in Figure 6.

To effect the required alternation of the application of a vacuum a distributing valve 27 (Figures 4 and 9 to 14) is provided for distributing connection from a vacuum manifold 40 alternately to a feeding manifold 42 connected to the interiors of all the feed rolls; and to a retaining manifold 41 connected to the interiors of all the guide members 26. Vacuum is supplied to the manifold 40 through a vacuum supply pipe 46 from a suitable source of vacuum, not shown. The manifolds 41 and 42 are elongated box-like structures secured to the side casing 22 as shown in Figures 4 and 9 and extending parallel to and near the line of bearings for the hollow shafts 60—61 of the feed rolls and guide members, for connection to the interior of the rolls and guide members through individual cut-off valve connections to be described below. The vacuum manifold 40 is a similar box-like structure, but shorter, as shown in Figures 4, 9 and 10. All three manifolds 40, 41 and 42 have a common flat outer face portion in which is formed the distributing ports 43, 44 and 45 communicating with the interiors of the manifolds 40, 41 and 42, respectively, and over which face portion the valve element 27 slides.

The distributing valve element 27 (Figures 4 and 9 to 14) has formed within it a distributing passage-way 140 open toward the said flat face portion with the defining edges of the opening in substantially vacuum tight, sliding contact with the said flat surface portion for establishing communication alternately between port 43 leading from the manifold 40 and ports 45 and 44 leading into the manifolds 42 and 41, respectively. The distributing valve element 27 is mounted for vertical oscillatory movement over the ports 43, 44, and 45 by means of a swing arm 66 carrying the valve element 27 secured thereto and pivoted at 32 to the side cover plate 22. With reference to ports 43, 44 and 45 it should be noted that these are greater in length than width and extend in length along a radius of the arc through which the valve element 27 slides, the object be-

ing to provide the greatest practical area of port opening with the least necessary movement of the valve.

Oscillation of the swing arm 66 is effected by sliding link bar 28 which is guided in its direction of movement by brackets 38 and limited in extent of movement by a stop pin 29. The link 28 at its upper end passes back of the swing arm 66 and pivotally connects with the adjusting arm 67 through a pin 31 carried by the link and projecting through a wide slot in the swing arm 66 into engagement with a close fitting slot in the adjusting arm 67. This adjusting arm is pivoted in common with the swing arm at 32, at one end, and is angularly, adjustably, secured at the other end to the swing arm 66 through an arcuate slot and bolt connection as shown in Figures 4, 19 and 14. The adjusting arm 37 thus furnishes means for angular adjustment of the swing arm 66 relative to a given position of the link 28.

A substantially vacuum-tight air seal is afforded between the contacting surfaces of the movable valve element 27 and the surface position of the manifolds 40, 41, 42 over which it slides, by the fact that these surfaces are made smooth and flat so that their juncture is rendered self-sealing by atmospheric pressure. In addition, a light initial pressure is maintained by the contact strap 68 under which the valve element 27 slides.

Each feed unit assembly comprising a feed roll and its associated guide member 26, is connected with the manifold 41 and 42 through an individual, push-button cut-off valve 54, each valve situated on the right hand side wall of the machine at the end of one each of the window openings for convenient manipulation by the right hand little finger of an operator loading the machine with sheets to be operated upon. The valve elements 54 are slidably mounted upon a seal plate 47 (Figures 5 and 8) preferably of composition material secured to the side wall of the machine, the sliding attachment being effected by means of a pair of tension screws 55 which pass through slots 56 in the valve element into threaded engagement with the seal plate. The slots 56 run lengthwise of the sliding valve element 54 and are of a given length permitting a predetermined limited sliding movement of the movable valve element, suitable spring washers 50 being provided beneath the screw heads bearing against the valve element over the sides of the slots to maintain contact tension between the valve element 54 and the seal plate. Connecting passages 57 and 58 in the valve elements are arranged one to connect a pair of ports 51—49 in the seal plate, and the other to connect a pair of ports 50—48 in the seal plate, in the depressed position of the valve, as shown in Figure 9 and as is the position of the fifth valve element from the top in Figure 5. In the extended position of the valve element as indicated for the four valves from the top in Figure 5, the passages 57—58 are moved out of connection with the ports 49 and 48.

The ports 48 of all the cut-off valves make connection through the side casing 22 to the retaining manifold 41 (Figures 4 and 9 to 12), while the ports 49 make similar connection with the feeding manifold 42. Ports 50 connect at the inside surface of the seal plate 47 with the interior of the hollow shafts 61 of the guide members 26 (Figures 8 and 9), while ports 51 make similar connection with the hollow shafts 60 of the feed rolls 25. Similarly, the feed unit assembly comprising the master feed roll 105 and 75

its associated guide member 106 is connected through an individual cut-off valve 112, seal plate 111 and a pair of extension pipes 117-118 with the manifolds 42 and 41.

To establish a substantially vacuum-tight seal at the ends of the hollow shafts 60 and 61 (Figures 5 and 8) the ends of the shafts, which terminate in flat annular surfaces, pass through journal openings in the side plate 22 of the casting into abutment with the inner surface of the seal plate 47 about the port openings 51-50 in the seal plate, the ports 50-51 in the seal plate being made smaller than the journal openings in the plate 22 for this purpose. The right hand shaft ends thus have lateral bearing in the openings in the plate 22 and a thrust bearing against the inner face of the seal plate. The thrust is supplied in the case of the shafts 60 of the feed rolls 25, each by a thrust spring 52 surrounding the bearing shaft 141 and bearing against the left hand side plate 23 and the left hand end of the feed roll 25; and in the case of the shafts 61 of the guide members 26, by a thrust spring 53 within the bearing socket 77 which receives the journal shaft 75 of the guide member 26. Similarly, a substantially vacuum-tight seal is provided for the ends of the hollow shafts 110 and 113 of the master roll and guide member through the use of a thrust bearing contact with the inner surface of a seal plate 111 maintained by thrust springs at the left hand ends of the roll and guide member arranged in a manner similar in all respects to the thrust springs of the feed rolls 25 and guide members 26.

The principal object of the thrust bearings and thrust springs is to cause the hollow journal shafts of both the feed rolls and guide members to bear against their respective portions of the seal plate 47 with a light but sufficient force to ensure contact which will be continuously airtight through an arc of rotation of the feed rolls and guide members. For this purpose, it is contemplated that the thrusting ends of the hollow journal shafts be finished with a smooth surface with which to contact the seal plate 47, and that the thrust springs 52 and 53 shall be only of sufficient strength to maintain the mechanical contact since by the effect of atmospheric pressure the joint is rendered self-sealing.

To effect proper timing or synchronization of the operation of the valve element 27 with respect to the operation of the feed rolls, the slide bar 28 for imparting motion to the swing arm 66 is driven by the main operating lever 34 through the pivotal screw 33, the operating lever fulcruming about the pivotal screw 35, which latter is held stationary during initial downward movement of the outer end of the operating lever until the bar 28 is stopped in its upward movement by a stop pin 29 fixed with reference to the machine casing. The pivot screw 33 then becomes the stationary pivotal point for further downward swinging movement of the outer end of the operating lever for operation of the feed rolls. The operation of the valve mechanism is thus timed in relation to the operation of the feed rolls to effect complete upward movement of the valve element 27 before any movement of the feed rolls. This timing is accomplished by taking advantage of the fact that the force required at the pivotal screw 35 to move the link 36 downwardly against the load offered by the several feed rolls and their operating mechanism is considerably greater than that required to operate the slide bar 28 and elements driven thereby from the pivot

screw 33 at the inner end of the operating lever. Similarly, when the lever 34 is moved upwardly by force of the retractile spring 39, the pivotal screw 35 remains stationary during initial upward movement of the outer end of the lever 34 while the lever pivoting about the screw 35 moved the bar 28 downwardly until the latter is stopped by the stop pin 29 in the lowermost position as indicated in dot-and-dash lines in Figure 4. The pivotal screw 33 then becomes the pivotal point for further upward movement of the outer end of the operating lever which continuing to move upwardly under force of the retractile spring 29, moves the link 36 upwardly to effect oscillation of the feed rolls 25 as previously described.

Motion is transmitted from the slide link 28 through pivot 31 to the adjusting lever 67 to swing the latter upwardly about the pivot 32 and with it the swing arm 66 and valve element 27 from the lowermost position shown in solid lines in Figure 4 into the uppermost position as shown in dot-and-dash lines in Figure 4. The width of the distributing passage-way 57 in the distributing valve 27 where it lies over the vacuum supply port 43 is so proportioned in relation to the arc of swing and the width of the port 43 as to remain in communication with the latter throughout the full extent of the swinging movement of the valve element 27, while that portion of the passage-way 140 which slides over the ports 44 and 45 is so proportioned in relation to its arc of swing and the spacing between these ports, as shown in Figures 11 and 12, as to communicate with but one of these ports in either extreme position of the valve element 27. Thus, with the distributing valve element 27 in the lowermost position as in Figure 11, the vacuum supply manifold 40 is put in communication with the retaining manifold 41 by way of ports 43 and 44 and the distributing passage 140 while the feeding manifold is opened to atmosphere through port 45. With the valve element 27 in the uppermost position, the manifold 40 is put in communication with the feeding manifold by way of the passage 140 and port 45, and the retaining manifold 41 opened to atmosphere through port 44. Thus each of the manifolds 41 and 42 when disconnected from the source of vacuum is opened to atmosphere to destroy any partial vacuum remaining in the manifold or the hollow shafts connected therewith. The object of this is to provide a prompt vacuum break whereby the form sheet may be released promptly from either its feed roll or guide member once the vacuum application of the valve element 27 has caused the sheet to be secured to the suction slots of the other; in short, to avoid the paper being moved when it is supposed to be retained against movement, or retained when it is supposed to be moved.

In the intermediate position of the valve element 27 as indicated in Figure 12, both ports 44 and 45 are in communication with port 43 through the distributing passage 140 for the purpose of effecting an application of the vacuum to one manifold 41 or 42 before disconnecting and opening the other to atmosphere.

To facilitate loading of the machine with the form sheets 59 to be worked upon, the guide members 26 are rendered retractable each with respect to its respective feed roll 25 by being mounted on journal shafts 61 and 75 for oscillatory movement to and away from its feed roll. In Figure 6 the guide members 26 are shown in the operating position, with their mating surfaces bearing upon the form sheets against the

feed rolls to guide and hold the form sheets in contact with the feed rolls. In Figure 7 the guide members 26 have been swung away from their respective feed rolls until their lower forward edges opposite their mating surfaces rest against those feed rolls which are next below in their assembled relation in the device. Simultaneous oscillation of the guide members to and away from the feed rolls is effected by means of 5 individual pairs of lever arms 70 and 73 (Figure 8) of spring wire, attached at one end to the guide member bearing shafts 61 and 75, respectively, and pivotally connected at the other end through pivot screws 85 and 142 to a pair of 10 common driving links 71 and 84. The purpose of making the lever arms 70 and 73 of spring wire is to provide means for distributing motion from the rigid driving links 71 and 84 to the several different guide members 26 under equalized tension, the tension being relatively light and 15 preferably not substantially more than sufficient to hold a work sheet in light contact with a feed roll. Reciprocation of the driving links 71 and 84 in unison is effected by means of their pivotal 20 connection through pivot screws 86 and 93 with connecting rods 87 and 91 journaled upon eccentrics 88 and 92. The eccentrics 88 and 92 are arranged to be rotated by a shaft 89 to which they are secured by keys 90 and 94. This driving 25 shaft is journaled at the left hand end (Figure 8) in a socket bracket 95 (Figures 8 and 15) secured to the side plate 23, which bracket is provided with a longitudinal extension around substantially half of its open end for engagement with 30 a stop pin 96 fixed in the shaft to limit rotation of the latter to substantially 180 degrees. At its right hand end this shaft is journaled in an opening in the side plate 22 and provided with a stop collar 97 bearing against the side plate to prevent longitudinal displacement of the shaft. An 35 external lever 98 fixed to the right hand end of that shaft serves to operate the latter not only for applying and retracting the guide members 26 but for regulating the pressure under which this is done.

Two further details of the guide members 26 may be described at this point:

The first of these is the loading ledge 78 (Figures 6, 7, 17 and 18). This consists of a longitudinal ledge or shoulder extending along the entire length of the lower outer edge of the guide member 26 opposite the concave mating surface. Referring to Figure 7 wherein members 26 are shown in the retracted position, it will be seen that it is this ledge which rests against that feed roll next below in the assembled relation. This same view shows the form sheet 59 which has been thrust between the members 25 and 26 and its upper or forward edge stopped by coming in contact with loading ledge 78. It is the purpose of the loading ledge to provide linear register of identical form sheets by forming a stop against which their respective upper edges may be similarly positioned.

The second of these details is the loading ledge stop pin 79 set into loading ledge 78 adjacent either of its ends, preferably that on the operator's right (Figures 2, 6 and 7). It provides a stop or guide for that corresponding edge of the 60 form sheet determined by the choice of location just offered. Its purpose is to provide columnar registration of identical form sheets by securing their similar lateral positioning along their respective loading ledges.

In connection with the two features just men-

tioned, it will be realized that the uppermost feed roll 25 is without a guide member above it for carrying a loading ledge and stop pin. To correct this deficiency the device is provided with a dummy guide member 81 (Figures 6, 7 and 8) whose 5 function is to carry a ledge and stop pin as designated by numerals 82 and 83, respectively. Obviously, the dummy guide member 81 may be substituted by another guide member 26, for which, of course, no vacuum passages need be 10 included.

To aid in the placement of the form sheets on the feed rolls, a pair of loading spring fingers 135 (Figures 6, 7 and 20) are provided for each of the feed rolls, attached to the lower edge of a 15 curved flange 136 extending downwardly and inwardly from the top edge of each window opening 134 toward the upper front portion of the feed roll associated with such window. These loading 20 spring fingers are preferably of thin spring brass or similarly suitable material.

During the placement of a form sheet in the device with the guide members in the retracted position as shown in Figure 7, it is of advantage to have the feed rolls 25 in the angular position 25 shown in Figure 6 and the vacuum applied to their suction slots. For this it is necessary that the main operating lever 34 be held down in the position shown in dot-and-dash lines in Figure 4 in order to hold the distributing valve 27 in the 30 uppermost position where it will maintain connection of the vacuum manifold 40 with the feed roll manifold 42. To enable this to be accomplished while leaving both hands of the operator free to manipulate the form sheet, a loading latch 35 104 is provided in the form of a bolt arranged to be moved into a position across the top of the lever 34 in the lower position of the latter to hold it in the depressed position against the tension of the retractile spring 39.

In operation, at the beginning of the loading of the device, all unit cut-off valves 54 and the master unit cut-off valve 112 are placed in the "off" position, that is up or towards the operator, which is the position of the four uppermost valves 45 54 in Figure 5, and the main operating lever 34 latched down in the position shown in dot-and-dash lines in Figure 11. By turning the guide member operating lever 98 to rotate the eccentric 50 89, the eccentric 88 is moved into the position shown in Figure 7, which moves the driving link 71 upwardly to rotate all the guide members 26 into the retracted position shown in Figure 7.

From a stack of form sheets which are to be computed and which have been arranged in the 55 desired order, the operator now takes up the top sheet; this, if the sheets are to be discharged in the same order, is applied to the top feed roll. To do this, the operator using both hands and holding the sheet in its proper position (with respect to readability), thrusts the lower end of the sheet down through the window opening of the top feed roll (Figures 3 and 7) and on down through the space between the feed roll and its associated guide member 26 into the passage-way 60 65 between the support 120 and the guiding vane 119 as shown in Figure 7.

Next, the operator retaining his hold on the top end of the sheet 59, places the upper end over the feed roll 25, entering the forward edge of 70 the sheet in the narrow space between the spring fingers 135 and the feed roll. Then the form sheet is held down in contact with the suction slots 62 of the feed roll and slid forward around the feed roll until its forward edge abuts the 75

loading ledge 82 of the dummy guide member 81 (in the case of the uppermost feed roll) thus providing the initial linear loading register of the form sheet upon the feed roll.

5 Still held upon the feed roll and against the loading ledge, the sheet is now slid to the right until its right hand edge is stopped by coming in contact with the loading ledge stop pin 83 which provides the initial columnar loading register 10 of the form sheet upon the feed roll.

15 With the sheet held in this position, the operator uses the little finger of the right hand to press down the uppermost, cut-off valve 54 to the "on" position which is the position as shown for the last five cut-off valves 54 in Figure 1. This applies the vacuum to the uppermost feed roll and the sheet is now thus secured to its suction slots.

20 This vacuum connection may be traced as follows: supply pipe 46 (Fig. 4), vacuum manifold 40, port 43 (Figure 10), distributor passage 140, distributor valve 27, port 45 into manifold 42, top port 49 in seal plate 47 (Figures 4 and 5), passage 57 in top cut-off valve 54 (Figures 5 and 8), and port 51, to hollow shaft 60 of the uppermost feed 25 roll.

25 The remaining feed rolls 25 are loaded in precisely the same way. It should be noted in their case that the loading ledge 78 and stop pin 79 of the preceding guide member 26 are used to obtain the linear and columnar register of the form sheet.

30 Next by movement of the eccentric operating lever 98 all the guide members 26 are moved to the contacting or operating position shown in Figure 6.

35 Should it be desired to load the master feed roll 105, this may be done at this stage, the register of its form sheet or key sheet being obtained through manual manipulation of the guide member 106. After the master form sheet is properly positioned, its cut-off valve 112 is pushed back into the position shown in Figure 5 to complete a vacuum connection to the interior of the master feed roll which connection may be traced from manifold 42 (Figure 4), pipe 117, upper passage 110 of cut-off valve 112 (Figure 5), hollow shaft 110 (Figures 2 and 3) to interior of master feed roll 105.

40 The main operating lever 34 is now released by withdrawing the latch 164, permitting the lever to move up under tension of its retractile spring 39 into the position shown in full lines in Figure 4, which effects a shifting of the vacuum from the feed rolls to the guide members 26 and consequently a retention of the form sheets 45 to their respective guide members, and further, rotates the feed rolls 25 backward (clockwise in Figure 4 and counterclockwise in Figure 7) into the position shown in Figure 7. This operation 50 takes place as follows: The upward pull on the lever 34 by retractile spring 39 causes the lever to first pivot on pivot screw 35 before substantial upward movement of the link 36, pulling down on link 28 to rock the distributing valve 27 downwardly into the position shown in Figure 4. This 55 connects the vacuum manifold 40 with the interior of such guide members 26 as have been rendered effective by a rearward setting of their respective cut-off valves. This vacuum connection 60 may be traced from vacuum manifold 40 (Figures 4, 5 and 9) through port 43, distributing valve 27, port 44, retaining-manifold 41, ports 48 of the individual cut-off valves, passage-ways 58 of the cut-off valves, ports 50, and hollow shaft 70 61 to the interior of the guide members 26 (Fig-

ure 6). After downward movement of the link 28 is stopped by the stop pin 29, the lever 34 continuing its upward movement under tension of spring 39 pivots about pivot screw 33 to move the link 36 into the uppermost position as shown 5 in solid lines in Figure 4 to rotate the feed rolls backwards in a manner as previously described.

10 The operator now depresses the main operating lever 34 which first pivoting about pivot screw 35 swings the distributing valve 27 to the top position shown in dot-and-dash lines in Figure 4, to shift the vacuum connection from the guide members 26 to the feed rolls 25, and then pivoting about pivot screw 33, pulls down link 36 to move the feed rolls in a clockwise direction (Figure 6) 15 to advance the form sheets 59 upwardly past their respective window openings toward the rear of the machine. The extent of movement of the sheets is controlled by the operator by limiting the length of the downward stroke of the operating lever 34 to that necessary to move the form sheets an amount sufficient to expose their like linear spaces simultaneously at their respective window openings 134 (Figure 1).

20 The operator now releases the lever 34 which returns to its uppermost position as shown in Figure 4 under tension of the retractile spring 39. The first degree of this movement shifts the vacuum connection from the feed rolls 25 to the guide members 26, to effect a release of the form 25 sheets from the feed rolls and their retention by the guide members, further upward movement of the lever effecting a backward rotation of the feed rolls to the position shown in Figure 6 all in a manner as above described in connection 30 with the previous release of the operating lever from the loading latch 104.

35 Thus, any given downward movement of the operating lever 34 results in a corresponding movement of all the form sheets upwardly 40 through the space exposed through their respective window openings, while any upward release of the lever results in a retention of the form sheets by the guide members with a reverse rotation of the feed rolls independently of the 45 sheets.

40 As the master feed roll 105 and the vacuum connections to it and its guide member 106 are controlled in synchronism with the feed rolls 25 and guide members 26, through the linkage 101 50 and 107, and pipe connections 117 and 118, the master sheet, when used, will be fed along in synchronism with the form sheets.

45 As the form sheets are fed step-by-step around the feed rolls they pass back into the passage-ways formed by the stationary supports 120 to 55 126 and the top guiding vane 119, and after release from the feed rolls slide down by gravity along the supports 120 to 126 to the discharge 60 opening 132.

50 The complete feeding through of the form sheets and master sheet is thus obtained by a series of successive forward movements of the nature just described. For the sake of flexibility 65 in use, the operating lever is arranged to have an extent of movement more than sufficient to effect a progression from line to line of the widest, practical, form-sheet spacing, within the compass of a single downward stroke.

55 While I have herein shown and described a specific embodiment of the invention for the sake of disclosure it is to be understood that the invention is not limited to such specific embodiment, but contemplates all such variants and modifi- 75

cations thereof as fall fairly within the scope of the appended claims.

What is claimed is:

1. In a tabulating machine for simultaneously bringing similar portions of each of a plurality of data sheets into a position for tabulation of data therefrom, a plurality of data indicating means arranged substantially side by side so that the data bearing portions of the sheets advanced thereto may be viewed simultaneously for tabulating purposes, sheet feeding means, means for moving said sheet feeding means to and fro for repeatedly acting upon each of the sheets for moving the same relatively with respect to said data indicating means, and means rendering said sheet feeding means effective for advancing said sheets a portion of their length during movement of said feeding means in one direction and ineffective to move said sheets, when said feeding means is moved in the opposite direction.
2. In a tabulating machine for simultaneously bringing similar portions of each of a plurality of data sheets into a position for tabulation of data therefrom, a plurality of substantially parallel data indicating means arranged side by side so that the data bearing portions of the sheets advanced thereto may be viewed simultaneously for tabulating purposes, pneumatic sheet holding means, means for moving said sheet holding means to and fro for moving each of the sheets relatively with respect to said data indicating means, means for effecting a differential air pressure and operatively connected with said pneumatic holding means, and means rendering said pneumatic sheet holding means effective for advancing said sheets a portion of their length during movement of said holding means in one direction and ineffective when moved in an opposite direction, whereby each of said sheets is moved step by step throughout its length to bring different data bearing portions of the sheets into view with respect to said data indicating means.
3. In a tabulating machine for simultaneously bringing similar portions of each of a plurality of data sheets into a position for tabulation of data therefrom, a plurality of data indicating means arranged substantially side by side so that the data bearing portions of the sheets advanced thereto may be viewed simultaneously for tabulating purposes, pneumatic sheet holding means, means for moving said sheet holding means to and fro for moving each of the sheets relatively with respect to said data indicating means, means for effecting a differential air pressure and operatively connected with said pneumatic holding means, means rendering said pneumatic sheet holding means effective for advancing said sheets a portion of their length during movement of said holding means in one direction and ineffective to move said sheets when said holding means is moved in the opposite direction, and means for controlling the said means for rendering said pneumatic sheet holding means ineffective and effective in timed relation with the movement of said pneumatic sheet holding means.
4. In a tabulating machine for simultaneously bringing similar portions of each of a plurality of data sheets into a position for tabulation of data therefrom, sheet feeding means for moving the sheets to data indicating position, actuating means for moving the sheet feeding means in the direction of feed and in a reverse direction, means for holding stationary and independent of the feeding means the sheets being fed, means operated in unison with the said actuating means for rendering said sheet feeding means ineffective during movement of the sheet feeding means in said reverse direction, and means operable in unison with said actuating means for rendering said sheet holding means effective only during movement of the sheet feeding means in said reverse direction.
5. In a tabulating machine of the character described, a sheet feed roll, movable releasable work holding means fixed with respect to the feed roll for holding the sheet on the roll, a second releasable work holding means for holding the sheet stationary independently of the roll, means for oscillating the feed roll in the direction of feed and in the reverse direction, and means for actuating and releasing said holding means operable in unison with said oscillating means to maintain the movable holding means actuated and the second holding means released during oscillation of the roll in the direction of feed and to maintain said movable holding means released and said second holding means actuated during oscillation of the feed roll in said reverse direction.
6. In a tabulating machine for simultaneously bringing similar portions of each of a plurality of data sheets into position for tabulation of data therefrom, a plurality of feed rolls each for feeding one of a plurality of data sheets to be tabulated, a plurality of data sheet supporting elements situated one below each feed roll and extending downwardly and away therefrom to support a data sheet fed to and away from the feed roll below which it is situated, and means for rotating said feed rolls simultaneously all through the same angle to simultaneously feed the data sheets a given amount.
7. In a tabulating machine for simultaneously bringing similar portions of each of a plurality of data sheets into a position for tabulation of data therefrom, a plurality of open ended data-sheet passage ways arranged one above the other each with an open end terminating substantially in a common plane, a feed roll situated near the open end of each passage-way arranged to feed a sheet across its surface out of and back through the passage-way.
8. In a tabulating machine for simultaneously bringing similar portions of a plurality of data sheets into a position for tabulation of data therefrom, the combination of a plurality of sheet feeding units each comprising a stationary sheet support, a sheet feed roll situated near the front end of the support for feeding a data sheet from off the support around the front of the feed roll and back onto the support, and means for simultaneously rotating the feed rolls of a plurality of units through substantially the same peripheral distance.
9. A tabulating machine for simultaneously bringing similar portions of each of a plurality of data sheets into position for tabulation of data therefrom, comprising a plurality of feed rolls for feeding the data sheets, said rolls being provided at their surfaces with suction openings extending around the surface through an arc less than the arc covered by the sheet, means for rotating the feed rolls, and means for limiting rotation of the feed rolls to an angle less than that of the arc covered by the sheet.
10. A tabulating machine as claimed in claim 9 in which the oscillation of the feed rolls is limited to an angle less than that of the arc covered

- by the sheet minus the arc of extension of the suction openings.
11. A tabulating machine as claimed in claim 9 in which a control valve is provided for controlling the connection of a source of vacuum with said suction openings, together with means for opening and closing said valve in timed relation with the rotating means. 5
12. A tabulating machine as claimed in claim 9 in which a control valve is provided for controlling the connection of a source of vacuum with said suction openings together with means for maintaining the valve open during substantially the entire limited rotary movement of the roll 10 in one direction, and closed during substantially the entire limited rotary movement in the reverse direction.
13. A tabulating machine as claimed in claim 9 in which a control valve is provided for controlling the connection of a source of vacuum with said suction openings together with means operable in timed relation with the rotating means to open the valve in advance of rotation of the roll in the direction of feed and to close the valve 15 after cessation of said rotation.
14. A tabulating machine as claimed in claim 9 in which a control valve is provided for controlling the connection of a source of vacuum with said suction openings, together with means operable in timed relation with the rotating means to maintain the valve open for a period of time including the entire time of rotary movement of the feed rolls in the direction of feed and to maintain the valve closed during a period including 20 the entire time of rotary movement in a reverse direction to the feed.
15. A tabulating machine of the class described, comprising a plurality of data sheet feed rolls, suction operated, feeding work-holders carried by the feed roll for holding a data sheet to the roll, suction operated, retaining work-holders each associated with one of said feed rolls for holding the data sheet independently of that roll, a distributing valve arranged to distribute connection from a source of vacuum alternately to 25 said feeding work-holders and to said retaining work-holders, means for simultaneously oscillating all of said feed rolls, and means operatively connecting said oscillating means and said distributing valve for operating said valve to maintain connection of a source of vacuum with the feeding work-holders during oscillation of the rolls in the direction of feed and to maintain connection of a source of vacuum with said retaining work-holders during oscillation of the rolls in a 30 reverse direction to the feed.
16. A tabulating machine as claimed in claim 15 in which the distributing valve and oscillating means are operated by a common mechanical operating means reacting against the oscillating means in operating the valve and against the valve in operating the oscillating means, and the oscillating means offers a higher mechanical load or resistance than the valve whereby the 35 valve is operated to the limit of its movement before operation of the oscillating means.
17. A tabulating machine for simultaneously bringing similar portions of a plurality of data sheets into position for tabulation of data therefrom, comprising a plurality of sheet feeding rolls, common actuating means for simultaneously actuating all of said rolls, sheet holding means for each roll carried by its respective roll for holding a data sheet on the roll fixed in relation 40 to the holder and roll, common control means for all of said holders, and individual control means one for each holder.
18. A tabulating machine as claimed in claim 17 in which the individual control means are situated each near one end of its respective feed roll and in reach of a finger of an operator's hand in the act of applying a sheet to the feed roll. 5
19. A tabulating machine as claimed in claim 17 in which the sheet holding means are vacuum operated, the common actuating means is a manifold between a source of vacuum and the several holding means with a valve controlling the connection of the source of vacuum with the manifold, and the individual control means are separate valves one for each holder controlling the 10 connection of its related holder with the manifold.
20. A tabulating machine for simultaneously bringing similar portions of a plurality of data sheets into position for tabulation of data therefrom, comprising a plurality of sheet feed rolls, a vacuum holding means carried by each feed roll for holding a sheet on that roll, a second vacuum holding means associated with each feed roll for holding the sheet stationary independently of that roll, common connecting means for connecting a source of vacuum alternately with all of said roll-carried holding means or all of said second holding means, and individual connecting means for individually controlling the 15 connection of said common connecting means to the holding means associated with one of each of said feed rolls. 25
21. A tabulating machine for bringing similar portions of each of a plurality of data sheets simultaneously into position for tabulation of data therefrom comprising in combination a plurality of feed rolls each arranged to support a data sheet bent thereover and of a diameter sufficient to so support and present to view a 30 complete one of the portions to be tabulated, and a master-sheet feed roll arranged to support a master data sheet bent thereover and of relatively larger diameter sufficient to support a relatively large portion of the master sheet at 35 a relatively slight curvature convenient for writing thereon.
22. A tabulating machine for bringing similar portions of each of a plurality of data sheets simultaneously into position for tabulation of data therefrom, comprising in combination, a plurality of data-sheet feed rolls each arranged to carry a data sheet looped therearound, means for oscillating said feed rolls simultaneously, a suction operated feeding work-holder carried by 40 each feed roll for holding a data sheet fixed in relation to the roll, a source of vacuum and a distributing valve operable in unison with the said oscillating means to maintain connection between said source of vacuum and the holder during oscillation of the feed roll in the direction of feed and to maintain the holder disconnected from the source of vacuum during oscillation in the reverse direction. 45
23. A tabulating machine for bringing similar portions of each of a plurality of data sheets simultaneously into position for tabulation of data therefrom, comprising in combination a plurality of data-sheet feed rolls each arranged to carry a data sheet looped therearound, means for oscillating said feed rolls simultaneously, a suction operated feeding work-holder carried by 50 each feed roll for holding a data sheet fixed in relation to the roll, a vacuum manifold connected to said suction operated work holders, 55
- 60
- 65
- 70
- 75

a source of vacuum, a distributing valve operable in unison with the oscillating means to maintain connection between the manifold and the source of vacuum during oscillation of the feed rolls in the direction of feed and to maintain the manifold disconnected from the source of vacuum during oscillation of the feed rolls in a reverse direction, and an individual cut-off valve element connecting the manifold individually with each work-holder.

24. A tabulating machine for bringing similar portions of each of a plurality of data sheets simultaneously into position for tabulation of data therefrom, comprising in combination, a plurality of data-sheet feed rolls each arranged to carry a data sheet looped therearound, means for oscillating said feed rolls simultaneously, a suction operated feeding work-holder carried by each feed roll for holding a data sheet fixed in relation to the roll, a suction operated retaining work-holder for holding the data sheet stationary, a feed vacuum manifold connected to said suction operated feed work-holders, a retaining vacuum manifold connected to said retaining work-holders, a source of vacuum, and a distributing valve operable in unison with the oscillating means to maintain the source of vacuum connected with the feed vacuum-manifold and disconnected from the retaining vacuum manifold during oscillation of the feed rolls in the direction of feed and to maintain the source of vacuum disconnected from the feed vacuum-manifold and connected with the retaining vacuum-manifold during oscillation of the feed rolls in the reverse direction.

25. In a tabulating machine for bringing similar portions of a plurality of data sheets simultaneously into position for tabulation of data therefrom, a sheet feeding device comprising a feed roll provided with a suction opening in the surface thereof of an arcual extent substantially less than the arc of contact of the sheet with a roll for holding a sheet on the roll, means for rotating said roll to feed the sheet, vacuum control means for connecting and disconnecting a source of vacuum to and from the said suction opening in the roll, and means connecting said rotating means and said vacuum control means for maintaining connection of the source of vacuum with the suction opening only through a given predetermined angle of rotation of said roller.

26. A tabulating machine of the class described comprising in combination a plurality of data sheet feed rolls arranged one above the other each for carrying a data sheet looped therearound, a guide member for each roll having a guiding face portion conforming to the roll and urged thereagainst under light tension for guiding the sheet into contact with the surface of the roll, a suction-operated feeding work-holder carried by each roll for holding the sheet on the roll in fixed relation thereto, a suction-operated retaining work-holder for each roll situated in the

said conforming face portion of the guide member for holding the sheet stationary independently of the roll, means for oscillating all of the feed rolls simultaneously through the same peripheral distance, and a distributing valve operable in timed relation with said oscillating means for alternately connecting a source of vacuum with said feeding work-holders at one time and said retaining work-holders at another time.

27. A tabulating machine as claimed in claim 26 in which the guide members are movable to move their conforming face portions away from their respective feed rolls to permit the placement of a data sheet on a roll.

28. A tabulating machine as claimed in claim 25 in which the guide members are movable to move their conforming face portions and retaining work-holders away from their respective feed rolls to permit the placement of a sheet on a roll and a work gauge for each roll for determining the initial positioning of a sheet on the roll and arranged to be moved into and out of close proximity to the roll surface, and means connecting said guide members and work gauges for moving the gauges into close proximity to the rolls upon movement of the guide members away from the rolls to permit placement and gauging of the sheets on the rolls, and away from the rolls upon movement of the guide members toward the rolls.

29. A tabulating machine as claimed in claim 26 in which the guide members are movable to move their conforming face portions away from their respective feed rolls to permit the placement of a data sheet on a roll; a common driving means for moving said guide members, and resilient individual motion transmitting means connecting said driving means with said guide members to limit the pressure exerted by the guide members against their respective feed rolls.

30. A tabulating machine of the class described comprising in combination a data-sheet feed roll, a guide member having a guiding face portion conforming to the roll, pivotal support for the guide member for moving the conforming surface portion of the latter to and away from the feed roll, and floating pivotal connection between the said conforming face portion and the pivotal support to establish alignment of the conforming surfaces of the roll and guide member by contact of the surfaces themselves.

31. In a tabulating machine of the class described, a sheet feeding member in contact with a sheet to be fed in a given direction, means for effecting a to-and-fro movement of the feeding member, a suction opening in said feeding member, and an air seal gasket for said suction opening arranged to contact with the sheet upon pressure of the sheet against the suction opening under suction and countersunk slightly within the surface of the feeding member to avoid contact with the sheet during the absence of an application of suction to the suction opening.

FLOYD DEFORD ELMORE.
